UNITED STATES PATENT OFFICE.

JOHN VERMEULEN, OF NEW YORK, N. Y., ASSIGNOR TO BERTHA FRANK,
OF SAME PLACE.

PROCESS OF MAKING OPEN-TWIST WIRE STRANDS.

SPECIFICATION forming part of Letters Patent No. 377,415, dated February 7, 1888.

Application filed June 16, 1887. Serial No. 241,576. (No model.)

To all whom it may concern:

Be it known that I, JOHN VERMEULEN, a citizen of Belgium, residing at New York, in the county of New York and State of New York, have invented certain new and useful Improvements in the Process of Making Open-Twist Wire Strands; and I do hereby declare the following to be a full, clear, and exact description of the invention, such as will enable others skilled in the art to which it appertains to make and use the same.

Heretofore these open-twist strands of wire have been made by twining or braiding two or more strands of wire around pins or single wires constituting the article intended to be made to form a true twist.

My invention is shown in the accompanying drawings, in which—

Figure 1 shows two wires coiled side by side around a mandrel so that the ends are delivered side by side. Fig. 2 illustrates the second step of the process of making this wire at B, while the third step, which is flattened by rollers, is shown at C. Fig. 3 shows a top 25 view of the completed strand.

The method of making these open-twist strands, as shown, is to coil two wires, A, on a suitable mandrel, and then stretch them out by drawing them off the mandrel, as shown at D, the two wires being thus interlaced, but not 30 technically twisted, as is readily seen from an inspection of Fig. 2. When these interlaced wires are sufficiently stretched and lengthened the proper distance to form openings of the desired size, they are passed between rollers and flattened, as shown at C, thus producing uniform openings of the desired size. 35

I claim—

The method of making open-twist wire strands, which consists in coiling two wires 40 side by side in one continuous coil, stretching the coil to the desired degree of openness, and flattening the stretched coil, substantially as set forth.

In testimony whereof I affix my signature in 45 presence of two witnesses.

JOHN VERMEULEN.
